UNITED STATES PATENT OFFICE.

FRED N. LA CHAPELLE, OF BEVERLY, MASSACHUSETTS, ASSIGNOR TO UNITED SHOE MACHINERY COMPANY, OF PATERSON, NEW JERSEY, A CORPORATION OF NEW JERSEY.

SHUTTLE-CASE.

1,146,001.

Specification of Letters Patent. Patented July 13, 1915.

Application filed July 23, 1910. Serial No. 573,367.

To all whom it may concern:

Be it known that I, FRED N. LA CHAPELLE, a citizen of the United States, residing at Beverly, in the county of Essex and State 5 of Massachusetts, have invented certain new and useful Improvements in Shuttle-Cases; and I do hereby declare the following to be a full, clear, and exact description of the invention, such as will enable 10 others skilled in the art to which it appertains to make and use the same.

The present invention relates to improved shuttle and bobbin cases for lock stitch shoe sewing machines.

15 In shuttle cases as now usually constructed a certain amount of longitudinal play is left whereby the bobbin case may be moved backward and forward, and when the thread is pulled down across the front 20 face of the bobbin case between it and the retaining door, the bobbin case is pushed backward by the thread to allow space for the thread to slip downwardly between the front of the bobbin case and the door. 25 Since there is this longitudinal free play allowed the bobbin case, the bobbin case must depend entirely upon the nicety of the bearing of its peripheral surface in the shuttle to resist any tendency to twist or 30 bind on its bearing. When the bearing between the bobbin case and the shuttle becomes worn from use, there is a tendency for the bobbin case to bind on its bearing and hence it will not always be freely 35 thrown backward by the thread, and in consequence the thread is caught between the front face of the bobbin case and the retaining door and snapped. Since the thread is pulled off through a thread delivering 40 button or projection on the front face of the bobbin case, whenever there is tension put upon the bobbin thread to set the stitch or to draw off a fresh supply of thread for the next succeeding stitch, there is a torque 45 or tendency to twist the bobbin case against its annular bearing about an approximately horizontal axis, drawing the top of the bobbin case forward, this being prevented only by the accuracy of the fit of the bobbin case 50 in its bearing, and as this bearing becomes worn there will always be some twisting of the bobbin case in its bearing when the thread is tensioned.

One object of my invention is to provide an improved shuttle case in which the

bobbin case may at all times be held positively in its position without loose play or any binding or twisting in its bearing, and at the same time to always provide a free space between the front face of the bobbin 60 case and the retaining door to allow the needle thread to freely slip therethrough.

The bobbin case as at present usually constructed has a solid front with a small oil hole. When the machine becomes heated in 65 use, the wax upon the cop or ball of thread in the bobbin melts and oozes out, causing the bobbin to stick in its case and also blocking up the oil hole, preventing the efficient oiling of the bobbin in its case. 70

Another object of my invention is to provide means whereby such wax as may melt and ooze between the bobbin and its case shall be automatically removed or scraped away, and to also provide means whereby 75 the bobbin may be easily oiled.

A still further object of my invention is to cut away certain parts of the shuttle mechanism, thereby lightening the parts and reducing their inertia. 80

My invention also contemplates certain other features of construction particularly defined in the claims.

In the drawings accompanying this application I have illustrated a preferred 85 form of my invention as applied to the well-known Goodyear rapid outsole stitcher which is illustrated and described in the patent to French and Meyer No. 473,870, April 26th, 1892. It will be understood, 90 however, that my invention is equally applicable to other lockstitch sewing machines, and that it can be otherwise embodied without departing from the spirit thereof.

Referring to the drawings Figure 1 is 95 a front elevation of the shuttle mechanism embodying my invention; Fig. 2 is a view taken partly in cross section along the line 2-2 of Fig. 1; while Fig. 3 is a front view similar to Fig. 1 and diagrammatically 100 showing the bobbin case in different positions.

Referring to the drawings, 1 indicates the stationary shuttle race or casing, 2 the oscillating shuttle-throwing shaft bearing upon its end the plate 3 provided with the shuttle-driving projections 4 and 5. A ring 6 secured to the shuttle casing by screws 7 retains the discoidal shuttle 8 in place by bearing against the peripheral flange 9 of 110

the shuttle. The construction and arrangement of these parts is substantially the same as the corresponding parts described in the patent to French and Meyer hereinbefore referred to.

Pivoted to the casing by any suitable locking hinge 10 is a bobbin case retaining door 11. This door is positioned upon the front of the bobbin case by having its flanged edge 12 fitting over the outwardly projecting lip or flange 13 formed upon the retaining ring 6, the door when locked in its closed position bearing against an annular stop shoulder 14 upon the retaining ring 6. The door has the usual guide groove 15 provided upon the interior thereof, in which the thread delivering button or projection 16 of the bobbin case 17 slides back and forth preventing the rotation of the bobbin case, at the same time there being sufficient space left between the button 16 and its groove 15 to allow the needle thread to be drawn therebetween, as provided in the structure described in the French and Meyer patent. The door has portions thereof at 18 and 19 cut away to lighten its construction and to allow free access to the bobbin case. The interior of the door is provided with an annular bearing surface 20 extending from a point marked 21 to a point marked 22, the lower portion of the complete circle of the bearing surface being cut away between points 21 and 22 to allow free space for the needle thread loop to slip on and off the shuttle. That central part of the interior of the door which is surrounded by the bearing surface, is recessed below the plane of the bearing surface sufficiently to allow a space between such central part and the bobbin case for a thread to slip through. The bobbin case 17 is provided with a thread feeding button 16, bobbin 23 and thread tensioning device of the usual construction, the bobbin case being held to rotatably turn in the shuttle. The front end face of the bobbin case is provided with the usual bevel edge 24 and toward the central portion of the front wall of the bobbin case are formed the cut-away portions 25, there being left an annular bearing space 26 of solid metal between the beveled portion 24 and the outer edges of the cut-away portions 25, except where the button 16 projects. This solid portion 26 just within the beveled edge 24 will at all times at some point of its surface be engaged by some part of the inner bearing surface 20 of the retaining door, the clearance of the shuttle case being such that no loose play of the bobbin case is allowed longitudinally between its rear bearing surface 27 in the shuttle and the bearing surface 20 upon the retaining door, the bobbin case thus being at all times held positively in place. The various positions of the bobbin case are diagrammatically shown as at A, B and C in Fig. 3,

while in Fig. 1 the bobbin case is shown in still another position marked D. When the bobbin case is in position A the front face of the bobbin will bear against the bearing or retaining surface 20 at *a*, while in the position B of bobbin case the bobbin case will be retained by bearing against a portion at *b* of the bearing surface 20. In the position D of bobbin case, it will bear at *d* against the bearing surface 20, and when the bobbin case is in position C it will be retained by bearing at two points *c c* against the bearing surface 20. Thus it will be seen that whatever position the bobbin case may assume it will be retained in place by the bearing or retaining surface 20 of the retaining door. When the beak 28 of the shuttle 8 is entering the loop of the needle thread, the bobbin case bears against the upper part of the bearing or retaining surface 20 as shown at *a*. As the shuttle is turned through the loop of needle thread the surface of engagement between the front surface of the bobbin case and its retaining surface 20 travels at first downwardly and to the left, as shown in Fig. 3, assuming in sequence the positions *b*, *c* and *d*. Thus it will be seen that, as the bobbin case is retained at a portion only of its surface by the surface 20, there will be a free thread slipping space between all other parts of the shuttle and bobbin case, and the retaining door. When the beak of the shuttle enters the loop of the needle thread there is a perfectly free clearance space between the bobbin case and the end 22 of the bearing surface 20, the bobbin case being retained by the upper part of the surface 20. As the thread travels over the shuttle, the surface of engagement between the bobbin case and retaining surface 20 travels downwardly to the left, the point of engagement of the bobbin case and the retaining surface 20 always traveling before the loop of thread until the front of the bobbin case finally slips off the lower end 21 of the bearing surface 20 and is engaged entirely by the end 22 of the bearing surface 20, the shuttle finally assuming the position shown in Fig. 1, which allows the thread loop to be pulled off between the end 21 of the bearing surface 20 and the bobbin case. It will thus be seen that there will always be provided a free clearance space for the needle thread to slip through between the front of the bobbin case and the door, as it travels about the shuttle.

There are two positions of the bobbin case in which tension is put upon the bobbin thread, first, when the stitch is being set in the work, this position being shown as at D in Fig. 1, and, second, when the bobbin rises and thread is pulled off the bobbin in preparation for the next succeeding stitch, this position of the bobbin being indicated as A in Fig. 3. It will be noticed that in both of these positions the bobbin case is held

in position by the bearing of its upper portion against the upper part of the retaining surface 20. This is of particular advantage since when tension is put upon the bobbin 5 thread there is a tendency to twist the bobbin case and draw its upper part forward. This twisting is entirely prevented in my improved shuttle case, the bearing surface 20 firmly holding in the upper part of the 10 bobbin case, even when the peripheral bearing between the bobbin case and the shuttle becomes worn by use, there being only sufficient clearance allowed between the bearing surface 20 and the bobbin case to allow the 15 shuttle to freely rotate. There is in both of these two positions a comparatively large surface of engagement between the bobbin case and the bearing surface 20, since in neither of these positions is the bobbin case 20 near the position marked C where part of the bearing surface 20 is cut away.

Since the front of the bobbin case is cut away at 25 the bobbin itself is exposed through these cut-away portions. When the 25 melted wax oozes or works between the bobbin and its case, the sharp inner edges of these perforations 25 serve to scrape the wax from the front surface of the bobbin, and the wax thus scraped will fall downwardly 30 free from the mechanism, and cannot clog the machine. These comparatively large openings 25 allow sufficient space so that the bobbin itself may be easily oiled, the cut-away portions 18 and 19 of the door allowing 35 easy access to the front of the bobbin case. In the form of door as now usually constructed the bobbin case strikes against the door not only near its edge, but also at points which are nearer to the center of its 40 front surface so that with the present form of door, it is necessary to use a bobbin case with a solid front face, and it is not possible to use a bobbin case having comparatively large cut-away portions 25 which I am enabled 45 to employ in my improved device, since the outer edges of these cut-away portions would catch on the usual form of retaining door. In my device, since the bobbin case bears against the door only near its 50 edge, I am enabled to cut away comparatively large portions of its front surface to allow the inner edges of these perforations 25 to scrape away the wax, afford easy oiling, and also lighten the construction of the 55 bobbin case. This I am enabled to accomplish by the combination of a bobbin case with portions of its front wall cut away, together with a retaining door which affords means for retaining the bobbin case in place 60 by bearing against the front face of the bobbin case only at points near its circumference.

Having thus described the nature and scope of my invention, what I claim is:—

65 1. The combination of a shuttle case com-

prising a retaining front having an interior annular bearing surface and a bobbin case having portions of its front walls cut away, whereby the bobbin may be automatically cleaned, substantially as described. 70

2. The combination of a shuttle case comprising a retaining front having an interior annular bearing surface and a bobbin case always bearing at points near the periphery of its front wall against said annular bearing surface, the front wall of the bobbin case being cut away at certain points lying within that part of its surface engaged by the annular bearing surface, substantially as described. 75

3. The combination of a bobbin case and a shuttle case comprising a closure having a bearing surface which retains the bobbin case in all positions by bearing on the bobbin case at points near the periphery of its front wall, certain points of the front wall of the bobbin case being cut away, whereby the bobbin is partially exposed, substantially as described. 80

4. A sewing machine, having, in combination, a discoidal shuttle, a bobbin case mounted in the shuttle to be carried by the shuttle in a circular path about the axis of rotation of the shuttle, and a shuttle case having a substantially flat annular bearing 90 surface adapted to bear against the end of the bobbin case to retain it in the shuttle, substantially as described. 95

5. A sewing machine, having, in combination, a rotary shuttle, a bobbin case mounted in the shuttle to be carried in a circular path about the axis of rotation of the shuttle, and a shuttle case having an annular bearing surface adapted to bear at all times against a single point near the periphery of 100 the end face of the bobbin case, said point of contact traveling continuously along the face of the bobbin case during the motion of the shuttle, whereby the bobbin case is retained in the shuttle and a free thread slipping space is always provided between the face of the bobbin case and the said bearing surface, substantially as described. 105

6. A sewing machine, having, in combination, a discoidal shuttle having a circular recess adapted to receive a discoidal bobbin case located eccentrically of the shuttle, a bobbin case and a shuttle case having a substantially flat annular bearing surface adapted to bear against the end face of the bobbin case, substantially as described. 110

7. A sewing machine, having, in combination, a discoidal shuttle, a discoidal bobbin case rotatably mounted in the shuttle eccentrically to the shuttle, and a shuttle case having a substantially flat annular bearing surface lying in a plane at right angles to the axis of rotation of the shuttle and adapted to contact with an end face of the bobbin case, substantially as described. 115

8. A sewing machine, having, in combination, a discoidal shuttle, a discoidal bobbin case rotatably mounted in the shuttle eccentrically to the shuttle, and a shuttle case having a smooth annular bearing surface adapted to bear against the bobbin case to retain it in the shuttle, substantially as described.
9. A sewing machine, having, in combination, a discoidal shuttle having a cylindrical cup-like recess located eccentrically of the shuttle, a cylindrical bobbin case rotatably mounted in said recess and having a flat annular bearing surface on its end face, and a shuttle case having a surface adapted to bear against the flat bearing surface of the bobbin case to retain the bobbin case in the shuttle, substantially as described.
10. A sewing machine, having, in combination, a discoidal shuttle, a discoidal bobbin case supported within and carried by the shuttle in a circular path about the axis of rotation of the shuttle, and a shuttle case having an abutment bearing against the end of the bobbin case in all of its positions to retain it in the shuttle, the end of the bobbin case and the abutment being constructed and arranged to provide a free thread slipping space over the end of the bobbin case, substantially as described.

11. A sewing machine, having, in combination, a rotary discoidal shuttle having in its front face a circular cup-like recess located eccentrically to the shuttle, a discoidal bobbin case having a substantially flat front end face, a shuttle case comprising a door having an interior flat annular bearing surface substantially concentric with the shuttle adapted to always bear against the

front face of the bobbin case at some point near its periphery whereby the bobbin case is retained in the shuttle and a free thread slipping space is always provided between the bobbin case and the door, substantially as described.

45
12. A bobbin case for a wax thread sewing machine having a cup-like bobbin receiving recess and having an aperture with a sharp inner edge through the closed end of said recess whereby the face of the bobbin next said closed end is automatically cleaned, substantially as described.

50
13. A bobbin case for a wax thread sewing machine having a bobbin receiving recess and having means for automatically 55 clearing the surface of the bobbin of wax, substantially as described.

55
14. The combination of a bobbin case having a rear opening for the insertion of the bobbin and having a portion of its front 60 face cut away, and a shuttle case comprising a door having an interior bearing surface adapted to contact with the front face of the bobbin case and having an aperture cut through it within said bearing surface, substantially as described.

65
15. The combination in a wax thread sewing machine of a metallic bobbin upon which waxed thread is wound and a bobbin case 70 having a bobbin-receiving recess and provided with a scraper engaging the surface of the bobbin to scrape wax therefrom, substantially as described.
